UNITED STATES PATENT OFFICE.

HERBERT McCORNACK, OF GLEN RIDGE, NEW JERSEY.

CENTRIFUGAL SEPARATOR.

Application filed November 4, 1921. Serial No. 512,766.

This invention relates to centrifugal separators and especially to separators adapted for the separation of cream from milk, although many features of the invention are applicable to centrifugal apparatus intended for other purposes.

Stated generally, the objects of the invention are to improve the design of the separator bowl so as to increase the efficiency and capacity thereof; to improve the feed; to improve the milk and cream discharge; to improve the mechanical construction of the liner discs and other parts of the bowl; to improve the bowl mounting; to provide improved and simplified mechanism for driving the bowl and for lubricating said mechanism; to provide an improved milk can mounting; and generally to simplify and strengthen parts and to render the same easier running, more durable and more efficient.

Specific objects of the invention will appear in the course of the following description of certain preferred embodiments of the invention chosen to illustrate the principle thereof and the best mode now known to me for practicing the same.

In the accompanying drawings, which form a part of this specification,

30 Figure 1 is a front elevation of a separator embodying the invention in preferred form.

Figure 2 is a side elevation thereof.

Figure 3 is a detail view partly in elevation and partly in section, showing the can mounting.

Figure 4 is a vertical sectional view of the bowl and its casing showing also the bowl-spindle and bearings therefor, and parts of the gearing.

Figure 5 is a horizontal sectional view through the bowl, showing one of the liner discs in plan.

Figure 6 is a side elevation of one of the liner discs.

Figure 7 is a view partly in side elevation and partly in section of the distributing cone.

Figure 8 is a similar view of the bowl bottom and hollow shaft.

Figure 9 is a sectional view on line IX-IX of Figure 8.

Figure 10 is an enlarged fragmentary detail view in plan of the marginal portion of one of the liner discs.

Figure 11 is a sectional view on line 55 XI-XI of Figure 10.

Figures 12 and 13 are similar sectional views on lines XII-XII, and XIII-XIII, respectively of Figure 5 but on the same scale as Figures 10 and 11.

Figure 14 is a vertical sectional view showing the feed cup and float controlled valve in a different position from that shown in Figure 4.

Figure 15 is a view partly in elevation and 65 partly in section of the dividing cone.

Figure 16 is a vertical sectional view on an enlarged scale of the top of the bowl and associated parts, illustrating the construction of the milk and cream outlets.

Figure 17 is a similar view showing the 70 neck of the bowl.

Figure 18 is a view, partly in section and partly in plan of the bowl neck, parts being broken away as indicated by the line 75 XVIII-XVIII of Figure 17, the neck flange of the dividing cone being also shown in plan.

Figure 19 is a view similar to Figure 16, showing a modified construction, parts being 80 shown in side elevation.

Figure 20 is a sectional view on line XX-XX of Figure 19.

Figure 21 is a vertical sectional view through the gear and bowl cases, showing 85 the bowl-spindle and gearing in elevation.

Figure 22 is a sectional view on line XXII-XXII of Figure 21.

Figure 23 is a view of a cap for closing an opening in the gear case, when the separator 90 is used with the hand crank only.

Figure 24 is a rear elevation of the upper part of the separator, showing the application of an electric motor thereto.

Figure 25 is a fragmentary horizontal sectional view of a portion of the gear case, showing in plan the electric motor applied thereto.

Figure 26 is a side elevation of the upper part of the separator, showing a belt drive 100 applied thereto.

Figure 27 is a detail view showing the mounting of the idler arm of the belt drive device.

Figure 28 is a detailed sectional view on 105 line XXVIII-XXVIII of Figure 27, showing the mounting of the idler arm.

Figure 29 is a vertical sectional view

through the bottom of the gear case and a sight feed lubricator and drain cock attached thereto.

Figures 30 and 31 are vertical sectional views on lines XXX—XXX and XXXI—XXXI, respectively of Figure 29.

Referring to Figures 1 and 2, the separator in the form illustrated comprises a base or standard 1, upon which is mounted a casing 2, which contains the gearing for driving the bowl-spindle and bowl. 3 is the bowl casing, which forms a part of the gear casing, and on this bowl casing is mounted the usual "tin ware", which comprises the milk chamber 4 having a milk discharge spout 5; a cream chamber 6 and discharge spout 7 and the feed cup 8. Supported above the feed cup is the supply can 9 for the unskimmed milk.

Supply can mounting.

Figures 1, 2 and 3 illustrate a novel and improved mounting for the supply can, comprising a standard 10, in the form of a stout rod, which is fitted at its lower end in a socket 11 formed in the casting constituting the gearing casing. Means are provided for preventing this rod from turning in its socket, such for instance, as the cross pin 12 engaged by a notch in the bottom of the rod (see Figure 3). At its upper end, the standard is formed with a transverse wedge-shaped projection 13, which is engaged by a block 14, having a complementary wedge-shaped groove therein. This block is attached to the side of the supply can in any suitable manner. In the construction shown in Figure 3, it is tightly mounted in a cup 15, which is secured in a loop 16 formed in a strap 17 welded or otherwise attached to the side of the can. The upper end of the cylindrical part of the standard is also received within the cup 15. Attached to the supply can near the bottom is a strap 18, which is bent to provide a semi-circular bearing 19 engaging the side of the standard. The wedge-shaped projection 13 on the standard is so positioned that when the supply can is in position with its nozzle 20 directly over the center of the feed cup, the groove in the block 14 will fit down over the projection and the supply can will be firmly held in the position described and also will be lowered slightly towards the feed cup so that the nozzle 20 projects slightly below the upper edge of the feed cup. When the operation of the separator has been completed and it is desired to remove the supply can so as to permit the tin-ware and separator bowl to be removed for cleaning, it is merely necessary to swing the supply can 9 to one side. Owing to the wedge-shaped form of the projection 13 and the corresponding groove in the block 14, the can will be lifted slightly as the block is

forced to ride up on top of the projection, this lifting being sufficient to lift the bottom of the nozzle 20 clear of the edge of the feed cup. The milk and cream receptacles may then be removed and the bowl lifted out. 70 When the parts are again assembled, the supply can is merely swung back to its original position and the groove in the block drops down over the projection on the standard, thus locking the can in correct position. 75 The can may be removed from the standard by merely lifting it off.

Referring now to Figure 4, this shows the bowl 25 mounted within the bowl casting 3, and supported upon the upper end of the bowl spindle 26. The bowl comprises a shell 27 and a base 28, the base 28 having a tubular central portion 29, through which the milk is discharged to the interior of the bowl, and the bowl shell and base being secured together by the bowl nut 30, which screws on the upper threaded end of the hollow shaft 29 and engages the top of the neck 31 of the bowl shell. The nut 30 is provided with notches 32 adapted to be engaged by a spanner in order to tighten up or remove the nut. In the construction shown the bowl nut is also provided with an annular groove 33.

Feed regulation.

Mounted in a central opening in the bottom of the feed cup is a sleeve 40, which is provided with an inwardly projecting collar 41, near its lower end, this collar having a central orifice 42, which is immediately over the opening in the top of the hollow shaft 29 of the bowl. Depending below the collar 41, the sleeve 40 has a flange or extension portion 43 which extends into the groove 33 in the bowl nut, without, however, actually touching the walls thereof (see Figures 4 and 14). Mounted in the feed cup 8 is the regulating float 45, which may be of any suitable construction, and which carries the float valve 46 preferably in the form of an inverted cone which is adapted to be lifted into the lower end of the nozzle 20 of the supply can so as to reduce or cut off the flow from the supply can when the milk flows into the feed cup faster than it is taken up by the separator bowl. When the milk is flowing from the feed cup to the bowl faster than it is flowing from the supply can to the feed cup, then the float will fall and permit an increased flow from the supply can.

In addition to the valve 46, for controlling the flow from the supply can, I preferably provide a valve for controlling the flow from the feed cup to the bowl. This valve is also operated by the float 45 and in the construction illustrated comprises a sleeve 50, which fits within the sleeve 40 carried by the bottom of the feed cup, the fit between the sleeves being sufficiently loose to permit

the sleeve 50 to move freely up and down under the influence of the float 45. The sleeve 50 is provided with a series of perforations 51, which are adapted to register 5 with similar perforations 52 in the sleeve 40 when the sleeve 50 and float 45 are down. A guide pin 53 is preferably carried by the sleeve 50 and works in a slot 54 in the sleeve 40, so as to prevent the sleeve 50 from 10 turning with respect to the sleeve 40. Two or more horizontal rows of ports or perforations 51 and 52 are preferably provided, the ports in one row being staggered with respect to the ports in the other, 15 as this arrangement provides for the ports being moved out of register with a comparatively small amount of vertical movement of the sleeve 50 with respect to the sleeve 40. Any other suitable arrangement 20 of ports or of valve construction may be employed.

In operation, it will be seen that as the float 45 rises, showing that the milk is flowing into the feed cup faster than it is passing 25 to the bowl, the valve 46 will reduce the flow from the supply can to the feed cup and at the same time the movement of the sleeve 50 with respect to the sleeve 40 will cause the holes 51 and 52 to move partially 30 out of register, thereby reducing the flow from the feed cup to the bowl and preventing over-crowding of the bowl.

The flange 43, which extends within the groove 33 in the bowl nut, serves to prevent 35 the inrush of air between the orifice of the feed cup and the hollow shaft of the bowl. The rapid rotation of the bowl and the discharge of the milk and cream therefrom, will cause a strong suction 40 into the bowl at the inlet thereof, at the top of the hollow shaft 29, and in separators as heretofore constructed, the air has been permitted free access to the opening at the top 45 of the bowl. By excluding such free access of the air, however, by means of the flange 43, I preserve this suction in large part and cause it to act to draw the milk from the orifice in the bottom of the feed cup into 50 the bowl. As this suction varies, however, with the speed of rotation of the bowl, it will be seen that it will act to draw the milk into the bowl with greater or less rapidity, depending upon the speed of the bowl. As 55 the rapidity of separation within the bowl also depends upon the speed of rotation, it is found that the feed to the bowl is proportioned to the rapidity of separation, so that a substantially uniform degree of separation is secured by the construction described 60 at any speed of rotation of the bowl within practical limits of operation.

It will be understood that while I prefer to use the flange 43 extending into the groove 33 in the bowl nut as a means for 65 preventing the inrush of air into the bowl,

as this construction is very efficient for that purpose, any other construction or form of the upper part of the bowl or bowl nut and of the orifice of the feed cup, or equivalent parts, may be employed which will produce 70 such a relation between the inlet to the bowl and the means for feeding the milk thereto as to prevent or substantially resist the inrush of air into the bowl to satisfy the partial vacuum created therein. 75

It will thus be seen that with my invention, it is unnecessary to observe the usual precaution to operate the bowl only at a certain predetermined speed as uniform separation will be secured at all speeds at 80 which it is practicable to operate the separator. The use of the valve 50 for controlling the flow from the feed cup to the bowl, in connection with the means for utilizing the suction of the bowl, assists in the regulation 85 of the flow of the bowl in proportion to the variable suction thereof.

Figure 14 shows the float 45 in its upper position with the cone 46 almost closing the nozzle at the bottom of the supply can and 90 the holes 51 almost out of register with the holes 52.

Construction of bowl and liner.

In the construction illustrated, the bowl 95 shell 25 is of arched conical shape and its lower edge fits within a flange 60, at the margin of the bowl base 28. The bowl base is provided with a groove in which is a rubber packing ring 61, engaged by the edge of 100 the shell. The flange 60 is provided with the usual notch 62 in which fits a pin 63 on the shell so as to bring the shell and bowl base together always in the same relation. At the center of the bowl base is a low conical boss 65, from which rises the hollow shaft 29, and at the bottom of this hollow shaft are the slots 66, through which the milk coming down the shaft is discharged 105 into the bowl. The bowl base is preferably provided with a series of wings 67, which cause the positive rotation of the body of milk. These wings and the slots 66 are 110 preferably arranged as shown in Figure 9, from which it is seen that the slots are tangentially arranged with respect to the central opening in the hollow shaft, while the wings are immediately behind the slots in the direction of rotation of the bowl, so that the milk flows out across the faces of the 115 wings and is caused to assume the rotative velocity of the bowl with the least possible disturbance or churning action. The wings 67 may be formed integral with or attached to the bowl base in any suitable 120 manner. In the construction shown, slots of the form indicated by the dotted line 68 in Figure 8 are milled in the wall of the tubular shaft and bowl base and the similarly shaped wings are driven in these slots 125 130

and firmly caulked therein by driving down the metal at each side thereof.

Fitting over the tubular shaft 29 and resting on the bowl base is a division member 5 which divides the bowl space into a primary separation chamber marked 70 in Figure 4 and a secondary separation chamber 71. This division member comprises what may be termed a distributing cone 72 (see Figures 4 and 7), projecting from the upper end of which is a sleeve 73 formed to provide interior and exterior cream channels. At the bottom of the cone 72 is a horizontal flange 74, which rests on the bottom of the bowl and the edge of which projects beneath a shoulder 75 formed near the lower edge of the bowl shell (see Figure 4). When the bowl shell is clamped to the base by the bowl nut, this shoulder will hold the flange 15 of the distributing cone in firm engagement with the rubber packing 61, so that a tight joint is formed and leakage from the primary to the secondary separation chamber at this point is prevented. As shown in 20 Figures 5 and 7, the sleeve 73 has portions which fit closely against the hollow shaft 29, these portions being separated by channeled ribs 80. The channels 81 inside of these ribs serve to conduct the thickest cream, 25 formed of the large fat globules which separate from the milk as soon as it reaches the primary separation chamber, up to the cream outlet; while the spaces 82 between the ribs form channels which receive the 30 cream separated from the milk in the secondary separation chamber. At the tops of the channels 81, flanges 83 are preferably provided, as shown in Figures 4, 7 and 16, so as to somewhat reduce the outlets from these 35 channels. Near its top the distributing cone is provided with a series of holes 84 preferably corresponding in number with the number of wings 67 and which form outlets to 40 permit the milk to pass from the primary to the secondary separation chamber.

Mounted in the top of the secondary separation chamber is the dividing cone 90 (see Figures 4 and 15) which has at the bottom an outwardly turned flange 91 and which 45 has on its outer surface a plurality of strengthening and division ribs 92, which are shaped on their upper surfaces to conform to the contour of the bowl shell, so that when the latter is clamped in position, it 50 will press firmly down upon the ribs 92 and dividing cone. On its top, the dividing cone has a neck 93 provided with an offset portion 94 of reduced diameter and turned over at the top to form a flange 95, which is 55 preferably provided with a suitable cream notch 96 of desired depth.

Mounted in the secondary separation chamber of the bowl and filling the space between the distributing cone and the skimming cone are a series of conical liner discs. 60

The preferred construction of these are fully illustrated in Figures 4, 5, 6, 10, 11, 12 and 13. As illustrated the discs are formed of very thin sheet metal drawn between dies to the proper cone shape and turned over at 70 one or both edges to form strengthening beads. The formation of these beads at the outer edges is particularly advantageous. If desired, the beads at the inner edges may be dispensed with, although the use of a bead 75 at each edge as shown is found to be very satisfactory. The beads are preferably formed by curling the edge of the metal and then striking it between dies so as to flatten it out into a bead of three thicknesses of 80 metal, as shown in Figures 11 and 13. The beads should be struck with sufficient force to firmly consolidate the same and sufficient pressure may be applied to cause the metal to flow somewhat so as to be slightly thinner 85 in the layers of the beads than in the body of the disc. Means for spacing the discs are preferably formed at the same time that the beads are formed and as a part thereof. This is illustrated in Figures 5, 10 and 12, 90 where it is seen that raised portion or "lands" 103 are formed at intervals in the outer bead. These may be conveniently formed by providing notches in the dies which are used to curl the metal and to 95 strike down the curled edge to the flat shape. Where these notches occur, the bead will not be flattened down, but will be left of extra thickness. Furthermore, owing to the fact that the rolled over edge is not forced 100 down into a tight seam at these notched points, that portion of the edge of the metal which would form the interior layer of the seam in the other parts of the beads, will be flattened against the conical wall of the 105 disc, as shown at 104, these portions 104 serving to space the conical surfaces of the discs so as to insure the stacking of the discs in true concentric relationship. On the distributing cone 72, lugs 110 having conical 110 portions 111 are provided upon which the lowermost of the liner discs seats.

For insuring the assembly of the liner discs in proper angular position, suitable means are provided, such as the rib 112 on the cream channel sleeve (see Figure 5), which projects into notches 113 formed in the liner discs. When the liner discs are assembled, the lugs 103 are directly over one another, as shown in Figure 4, so as to provide what may be termed pressure transmitting columns, extending between the flange of the skimming cone and the lugs 110 on the distributing cone. When the liner and bowl parts are assembled and the bowl nut is screwed up, the bowl shell presses firmly 120 upon the ribs 92 on the dividing cone and this pressure is transmitted through the columns of lugs 103 to the bottom of the 125 bowl, so that all the discs are positively and 130

firmly located in position and are accurately centered and spaced. The liner discs are each provided with a series of holes 115, which when the discs are assembled, register 5 with the corresponding holes in the other discs and with the holes 84 in the distributing cone to form vertical columns of holes through which the milk is distributed between the discs. Preferably the liner discs 10 are made of a double pitch, the outer parts of the discs being of approximately 60° inclination, while the inner parts of the discs are of approximately 45° inclination, the distributing and skimming cones being 15 similarly shaped. Any other suitable form of disc may, however, be employed.

In the operation of the bowl, the milk entering the top of the hollow shaft 29 is delivered to the primary separation chamber 20 through the slots 66 in front of the wings 67 and is caused to rapidly revolve with the bowl. Heavy dirt or sediment will at once separate from the milk and will accumulate in the V-shaped space 120 at the periphery 25 of the primary chamber. The immediate elimination of the heavy sediment from the milk at this stage is very desirable as considerable quantities of this sediment can be accumulated in the space 120 without interfering 30 with the operation of the separator and the sediment is not carried into the narrow spaces between the liner discs, where it might tend to clog the same. While the milk is in the primary chamber, a preliminary 35 separation thereof takes place and the comparatively large cream globules which are most easily separated pass towards the center of the bowl and upward through the channels 81 toward the cream outlet. The remainder 40 of the milk from which this sediment and these large cream globules have been separated then passes through the holes 84 and 115, and is distributed between the liner discs, where the remainder of the cream 45 is separated and passes towards the center of the bowl, moving upwardly towards the cream outlet through the channels 82, the blue milk passing to the periphery of the bowl, upward and outside of the 50 edges of the discs and over the dividing cone between the ribs 92, to the milk outlet.

Owing to the fact that the sediment and the thickest elements of the cream have been removed from the milk before it enters the 55 secondary separation chamber, the total volume of milk to be handled in the secondary chamber has been diminished, and furthermore, those elements of the milk most likely to clog the narrow spaces between the discs have already been taken 60 out. Consequently there is less work to be performed in the secondary chamber, and therefore this chamber need not be so large as would be necessary if all the milk passed 65 between the discs, a smaller number of discs

may be utilized and smaller spaces may be provided between and around the discs. The spaces between the discs may also be made narrower owing to the fact that the thicker elements of the milk have already 70 been taken out and danger of clogging thereby reduced.

The construction of disc described lends itself to the use of very thin metal and owing to the accuracy with which the discs may be 75 made and to the accuracy of the spaces between them, due to their method of construction and assembly, the spaces between the discs may be made exceptionally narrow. This increases the efficiency of the bowl and 80 permits the same to be made smaller as a greater number of thin closely spaced discs may be stacked within a given space as compared with thicker discs not so closely spaced. 85

The double pitch of the discs is also desirable in the construction described, as this form of disc provides for a closer spacing of the steeply pitched part of the discs than of the central, less steeply pitched part. The bulk 90 of the cream passes out between the more widely spaced inner parts of the discs, while only the blue milk and a very small proportion of the cream enter between the steeply pitched parts of the discs, in the 95 very narrow spaces between which the small remaining portion of cream is separated out and only the blue milk passes through to the periphery of the bowl. The entire arrangement is exceedingly efficient and a much larger capacity may be obtained with a bowl 100 of given size than is possible with bowls of similar size at present in use. The space between the bowl shell and the edges of the liner discs is preferably made narrow so as 105 to cause the blue milk, which escapes between the margins of the discs and which passes upwardly through this space, to travel at a sufficient velocity to sweep along with it any casein or other sediment and carry the same out of the bowl. In this way an accumulation of sediment in the peripheral portion 110 of the bowl is avoided and the bowl may be operated for a long time without becoming clogged. With the construction of bowl described it is possible to make this peripheral space in the bowl very narrow as the heavier cream is removed from the milk in the primary separation chamber and the heavy sediment and dirt are also removed 115 in that chamber and accumulated in the space 120.

The fact that the peripheral space in the bowl may be made narrow for the reasons described permits the liner discs to be extended almost to the periphery of the bowl so that the greater part of the peripheral space which ordinarily serves merely as a storage space for sediment and as a conduit 125 for the blue milk is made useful for separat- 130

ing purposes. This reclaimed bowl space may be translated into skimming efficiency either by enlarging the diameter of the discs in proportion to a given diameter of bowl so as to increase the efficient flow capacity of a bowl of such given diameter, or the diameter of the bowl may be reduced for a given diameter of discs thus reducing the driving effort necessary for a given flow 10 capacity.

Milk and cream outlets.

The construction of the bowl neck and of the milk and cream outlets, shown in Figures 4, 16, 17 and 18, is as follows: The top of the bowl neck is provided with one or more notches 125 having upwardly and outwardly inclined bottoms (see Figures 16, 17 and 18). The bowl nut is provided with a narrow downward extension 126, which fits 15 within the top of the bowl neck and a shoulder 127 on the bowl nut fits against the top surface of the neck. Outside of the shoulder 127, the bowl nut is preferably beveled upwardly and outwardly, as shown at 128. 20 The notches 125 provide outlets for the cream which is delivered upwardly and outwardly between the inclined walls of these notches and the inclined surface 128 of the bowl nut. The thick cream from the primary separation chamber passes upwardly from the channels 81 through the openings 130 bounded by the flanges 83 and into the space inside of the reduced diameter portion 30 94 at the top of the skimming cone. At this point it mingles with the cream coming from the secondary separation chamber through the channels 82 and the entire cream from both separation chambers passes over the flange 95 at the top of the dividing cone and 35 through the cream notch 96 and is then discharged through the notches 125 into the cream chamber 6, as described. 40

Preferably the cream notch 96 is located 45 opposite one of the notches 125 and near the forward end thereof (in the direction of rotation of the bowl) as shown in Figure 18. This permits the cream to leave the bowl at the angular velocity of the bottom of the notch 96 instead of at the velocity of the diameter of the outside of the bowl neck, the approximate path of the cream being indicated by the broken line 97 in Figure 18. In ordinary use all of the cream will be discharged through the notch 96 in this manner, with a resultant minimum of churning 50 or frothing and a decreased driving resistance.

The blue milk coming from the periphery 60 of the bowl and over the dividing cone 90, passes into the annular space 131 formed inside of the lower part of the bowl neck, which is of larger diameter than the outside of the neck 93 of the dividing cone (see Figure 16). Above this space 131, the internal 65 diameter of the bowl neck is reduced as

shown at 132 (Figures 16 and 17) and through this part of the bowl neck are formed one or more narrow horizontal slots, two being shown at 133 and 134, respectively, (Figure 18). The rear end wall 135 of the 70 slot 133 (referring to the direction of rotation of the bowl—see Figure 18) and the rear end wall 136 of the slot 134, are preferably inclined rearwardly and in a generally tangential direction, so that the milk 75 leaving the bowl through these slots is permitted to leave the bowl neck as nearly tangentially as possible, so that it will be discharged with the least disturbance, and so that there will be as little frothing as possible. This tends to cut down resistance and lessens the power required to drive the bowl. The milk also leaves the separator in good condition. The bulk of the milk flows over the surface 132 of the bowl neck directly 80 to the slots 133 and 134, and these slots being long, the milk can flow out in a broad thin stream. In order to secure adjustment of the milk flow, so as to regulate the density 85 of the cream, a milk notch 137 is formed 90 adjacent to the forward end of the slot 133. The effective depth of this milk notch is governed by adjustable milk screw 138, which screws into a threaded opening 139 in the wall of the bowl neck, the screw being adjustable so as to advance its end more or less across the milk notch, thereby to vary the radius at which a portion of the milk may 95 pass through the notch to the slot 133. Whatever milk passes through the notch 100 over the end of the screw, is discharged through the wide slot 133 instead of through a small orifice as is customary in separators using a perforated milk screw, with the advantage that it is delivered from the bowl 105 at the radius of the inner end instead of that of the outer end of the screw and at correspondingly less velocity and with less loss of energy. The bowl neck is provided with a portion 145 above the portion 132, which 110 is of such diameter as to fit tightly against the outside of the reduced neck portion 94 of the dividing cone (see Figure 16) so as to prevent the milk passing up to the cream outlet. 115

In Figures 19 and 20, a modified construction of bowl neck and milk and cream outlets is provided, in which the cream channel sleeve 73 is provided at its upper end with an extension 150 of reduced diameter, which 120 extends upwardly to the level of or slightly above the milk outlet slots 133 and 134. The skimming cone neck 93 is provided with an inwardly extending rib 151 at a point below the top of the extension 150. With this construction, it will be seen that the cream passing from the primary separation chamber upwardly through the channels 83 will mingle with the cream passing through the channels 82, from the secondary separation chamber, at a point above the rib 151, which 125 130

forms a dam interposing a resistance to the downward movement of any traces of blue milk which may be present in the cream which has come up through the channels 83. 5 Thus the possibility of any counter-currents being set up which would interfere with the free discharge of the cream is prevented. The special value of this is to avoid the more exact adjustments of resistance in the bowl, 10 which otherwise would be necessary in order to regulate the flow proportions from the primary and secondary separating chambers.

Bowl mounting and spindle.

15 In the bottom of the enlargement 65 of the bowl base, a tapered hole 160 is formed to receive the tapered end of 161 of the bowl spindle 26. It will be seen that the point of engagement of these tapered surfaces 20 which constitutes the point of support for the bowl, is well below the center of gravity of the bowl and preferably as near the bottom of the bowl as is convenient. By using properly tapered surfaces, I find 25 that a sufficiently firm engagement is secured between the bowl and spindle to enable power to be transmitted from the spindle to the bowl for rotating the latter without the use of any cross pins, keys or the like. At 30 the same time the bowl may be very readily removed from the spindle by merely lifting it off. The engagement between the bowl and spindle while firm is not absolutely rigid but admits of the bowl tending to 35 right itself by reason of its gyroscopic or top-like action when it attains its high speed of rotation. The bowl spindle 26 is preferably made as short as possible and is supported at its lower end in a thrust bearing 40 162, and near its upper end, just below the bottom of the bowl, in a yieldable neck bearing 163. Mounted upon the spindle between the bearings and preferably as near the thrust bearing as possible is the spiral or 45 worm pinion 164, which is engaged by the downwardly rotating part of the spiral driving gear 165. By making the bowl spindle short and mounting the pinion 164 as near the thrust bearing as possible and by 50 the described manner of mounting the bowl on the spindle, I secure a true top-like action so that when the bowl and the spindle are running at high speed, they act like a spinning top, spinning upon the thrust bearing as a support. They tend to spin vertically in this manner with great steadiness and very little pressure upon the neck bearing so that smoothness and lightness of running are secured in a high degree with 55 very little friction and wear on the bearings and with the expenditure of a minimum amount of power for driving the bowl. Even if the separator is not set in such a way that the bowl spindle is absolutely ver-

tical smooth running will nevertheless be secured. 65

Bowl spindle bearings.

The bearings for the bowl spindle may be of any suitable character, but I have devised 70 a new construction for such bearings, which I prefer to use and which possesses advantages over bearings now in use. The construction of these bearings is particularly illustrated in Figure 4. Referring to the 75 neck bearing 163, this comprises an outer sleeve 170, which is slotted from the bottom nearly to the top at two or more points as indicated at 171. Ribs 172 are formed on the parts of the sleeve near the lower end 80 thereof these being adapted to engage the beveled surface 173 at the bottom of the cylindrical opening in the gear casing, which receives the neck bearing. The slots 171 permit the parts of the sleeve to yield sufficiently to enable the ribs to be forced through the opening in the casing and then snapped into place against the beveled surface. The bearing may thus be simply pushed into its seat or pulled out therefrom. 85 The sleeve 170 is flanged outwardly at the top, as indicated at 174. A second flanged sleeve 175 is mounted within the sleeve 170, a space 176 being left between the sleeves. The sleeve 175 is provided at the top with 90 an outwardly extending flange 177, which rests on the flange 174 and at the bottom is a narrow inwardly turned flange 178. At the top of the bearing is a cap 179, which rests on the flange 177, and which has its 95 edge rolled over the edges of the flanges 174 and 177 and interlocked with a bead or turned over edge on the flange 174, so as to firmly hold the bearing parts together. Supported on the flange 178 of the sleeve 100 175 is a bushing 180 of bronze or other suitable bearing material, which is preferably provided with a spiral oil groove 181 in its bearing face, the inclination of the spiral being preferably such that as the bowl spindle rotates, the oil will tend to work downwardly in the groove. Near the top of the bushing are a series of transverse holes 182 for admitting oil to the inside of the bushing. Interposed between the bushing and 110 the sleeve 175 is a ring 183 of yieldable material, preferably of cork composition, as this is a material which I have found to be sufficiently yielding for the purpose of absorbing the vibrations of the spindle and 115 to be durable and not injuriously affected by the oil. The resiliency of this member together with the fact that the bearing sleeves 170 and 175 are not absolutely rigid, provides all the yieldability necessary for the 120 bearing. Formed in the sleeve 175 at or about its point of conjunction with the flange 177 are one or more oil holes 184. In the 125

- operation of this bearing, a part of the mist of oil which is formed in the gear casing by the rapid rotation of the gears in the bath of oil in bottom of the casing, will pass up through the space 176 and holes 174 and 182 to the interior of the bushing. This oil is then fed back by the spiral groove and rotating spindle to the gear casing. The bearing is very satisfactorily lubricated in this way and practically no oil escapes from the top of the bearing into the bowl casing. The step bearing 162 comprises a plug screwing into a threaded opening at the bottom of the gear casing and adapted to be locked in adjusted position by a lock nut 190, the inner corner of which is preferably beveled off as at 191, so as to provide a space for a packing 192 of lead, asbestos or other suitable material. The upper end of the screw plug is provided with a recess 193 in the bottom of which is placed a layer of yielding material 194, preferably of cork composition. Upon this layer of yielding material rests a step bearing plate 195, of hardened steel, this plate preferably being of slightly smaller diameter than the diameter of the recess so that it is out of contact with the walls thereof. An oil drain hole 196 is preferably formed near the bottom of the recess. The bowl spindle preferably carries at its lower end a hard steel tapered plug 197, driven into a tapered bore in the spindle and having a rounded lower end bearing upon the surface of the hardened plate 195. Obviously, however, any other suitable form of end thrust bearing may be employed, although I prefer the construction described as it is very durable, practically frictionless and is noiseless.
- For the lateral support of the lower end of the bowl spindle, a bushing 200 is provided which rests on the plate 195 and which is surrounded by a ring 201 of yielding material, such as cork composition. This ring of yielding material is held in place by a sleeve 202 which fits firmly in the upper part of the recess in the screw plug. The outer diameter of the bushing is preferably such that it is out of metallic contact with the screw plug and sleeve 202. In the bearing described it will be seen that there is no metallic contact between the lower end of the bowl spindle and the gear casing and frame of the separator, as a result of which a very quiet operation of the separator is secured. The interior of the bushing 200 is preferably provided with a spiral oil groove 203, which is inclined in such a way as to cause the oil to work downwardly through the bushing, and a notch or hole 204 is formed at the bottom of the bushing to permit the oil working down through the same to escape and flow back through the hole 196 into the gear casing. An effective circulation of lubricant is thus maintained and metallic particles are carried by the oil out of the step bearing, finding their way to the bottom of the gear casing.
- Separator drive.*
- Where the separator is to be driven by hand, a suitable train of gearing is provided for driving the gear 165, which drives the bowl spindle. As illustrated in Figures 21 and 22, this gearing includes a pinion 210 mounted on the shaft 211, which pinion is formed on a sleeve 212 journaled on the shaft. The gear 165 is keyed or otherwise firmly secured to this sleeve. The pinion 210 is engaged by a gear 213, which is fixed to a sleeve 214, journaled on the intermediate shaft 215. The sleeve 214 carries a clutch member 216, which is provided with a spiral tooth 217. Journaled on the sleeve 214 is a pinion 218, which is provided with a spiral clutch tooth, adapted to engage the tooth 217 on the clutch member carried by the sleeve. The construction of these clutch teeth is such that when the pinion 218 is being driven, the clutch teeth will engage and the pinion will drive the sleeve 214 and gear 213. When the bowl is spinning, however, and no power is being applied, then the clutch teeth will be disengaged and the sleeve 214 will turn freely with the gearing connecting it with the spinning bowl and without carrying with it the pinion 218 and the gear in mesh therewith. In many hand driven separators a one-way coupling or clutch is provided on the shaft carrying the gearing which meshes directly with the bowl spindle pinion, or "high-speed" shaft, as it is sometimes called, but I find that there are decided advantages in utilizing this clutch in connection with the gearing on the intermediate shaft instead of the gearing on the high-speed shaft. One important advantage is that the clutch member and pinion do not rotate at such a high speed and therefore, there is less danger of injury thereto and greater durability is secured. Another important advantage is that in my construction, the intermediate gear 213 is rotating at all times when the bowl is rotating and as this is the gear which dips into the oil in the gear casing and is relied upon to create the oil mist which lubricates the parts, such lubrication is supplied with certainty at all times when the bowl is in motion. This is not the case where the clutch member is on the high speed shaft and in such construction the intermediate gear will remain stationary when not actually in use in driving the bowl. The construction set forth is especially advantageous in connection with the power driving means for the separator to be described.

For the hand driving of the separator, the pinion 218 is driven by the gear 220, which is fixed to the crank shaft 221, which carries the hand crank 222. The gears 210, 213, 218 and 220 are preferably spiral gears and the inclinations of the spirals are so arranged that the reactions of the two pairs of gears 210 and 213, 218 and 220, respectively, neutralize each other. The arrangement is preferably such that the re-actions between the gears 210 and 213 and the side thrust of the gear 210 is in the direction of the end bearing 225 on the side wall of the gear casing. The thrust of gear 213 is then in the opposite direction. The re-action between the gears 218 and 220 causes a side thrust of the gear 218 in a direction opposed to that of the gear 210 so that these two thrusts tend to neutralize each other. Furthermore, these two thrusts acting in opposite directions cause the clutch member on the pinion 218 to engage the clutch member 216 so that when the power is being applied through the pinion 218 to the sleeve 214 and gear 213 the clutch members will be caused to firmly engage. When power is not applied in this manner, however, the clutch members are not held in firm engagement, and therefore, will slide freely by one another. The side thrust on the gear 220 is taken up by the engagement of the inner surface 226 of the hand crank with the end of the boss 227 projecting from the side of the gear casing. The bottom of the gear casing is depressed, as indicated at 230 in Figures 21 and 29, so as to provide a chamber or trough to hold a supply of oil. As sufficient oil is maintained in this chamber so that the periphery of the gear 213 will dip therein, this gear, when in rapid rotation, will pick up some of the oil, spraying the same through the gear case and in fact, causing an oil mist, which will fill all parts of the gear case and thoroughly lubricate all bearings.

With the arrangement of the gearing described, in which the ratchet clutch device is arranged on the intermediate shaft 215, instead of being arranged on the high speed shaft 211, as is more customary, it will be seen that the gear 215 is travelling at all times when the bowl is spinning, whether the crank is being used to drive the separator or not. Consequently, whenever the bowl is spinning oil is being supplied to the bearings by the rotating gear 213. This is especially important where the power driving means about to be described are employed as it permits such power driving means to be utilized when directly connected to the gear 165, without any change being necessitated in the arrangements for lubricating the bearings. When the separator is to be utilized as a hand driven separator, no power driving means being attached. The bearing mem-

ber 235 shown in Figure 22, which forms a part of the power driving means is removed and a cap 236 as shown in Figure 23, is substituted therefor, this cap having a central projection 237, which bears against the end of the sleeve 212 and gear 165 and holds the latter in place. There is no substantial thrust against this cap, however, as the thrust of the gear 210 is towards the opposite side of the gear casing as already described.

Power driving means.

The construction of separator drive described is such that power driving means may be applied without necessitating any changes in the arrangement of the gearing or in fact any change at all except the removal of the cap 236 and the substitution of the member 235 with the power driving device carried thereby. Belt driving devices are shown in Figures 22, 26, 27 and 28. As here illustrated the fitting 235 has journaled therein a shaft 240, the inner end of which is slotted as indicated at 241 (see Figure 22), and which carries a collar 242 which is slotted at 243. A cross pin 244 extends across the slot 241, and mounted in the slots and maintained in position by this cross pin is a forked spring 245. The two arms of this spring project through holes 246 in the web of the gear 165, so that they establish a yielding torsional drive between the drive 240 and this gear. The drive shaft 240 has fixed to its outer end a pulley 250 arranged to be driven by a belt 251, (see Figure 26), by which power is transmitted to drive the shaft 240, gear 165 and bowl spindle. As already explained, when the gear 165 is driven the intermediate gear 213 will also be driven so that the bearings will be properly lubricated. The belt 251 preferably runs over a driving pulley 252 mounted on a standard 253 on the separator frame or other suitable support. An idler 255 is preferably provided for keeping this belt tight. A desirable mounting for this idler is illustrated in Figures 22, 27 and 28, where it is seen that the idler is mounted on an arm 256, which is journaled on the sleeve 257 forming an extension of the fitting 235. Also mounted on this sleeve 257 is a collar 258 which is adapted to be located in adjusted position on the sleeve 257 by a set screw 259. The collar 258 is provided with a lug 260, which projects into a recess 261 formed in the ring or head portion of the arm 256, which surrounds the sleeve 257. The lug 260 is capable of limited circumferential movement in the recess 261 and a coiled spring 262, mounted in a pocket 263 of the lug 260, bears against the end wall of the recess 261 so as to provide a yielding abutment for the lug 260. By the arrangement described, the desired tension may be

placed on the belt by adjusting the collar 258 by means of the set screw 259, a collar carrying with it the arm and idler. The spring 262 permits the arm and idler to yield slightly so as to prevent undue binding of the belt.

Where an electric drive for the separator is desired, a fitting 270 is used in place of the fitting 235 the fitting 270 carrying an electric motor 271 (see Figures 24 and 25), the armature of which is mounted directly on the shaft carrying the slotted ring 242 and forked spring 245, which engages the gear 165.

15 *Lubricating means.*

In Figures 29, 30 and 31, I have shown a means for supplying lubricant to the gear case and also for draining off sediment from the gear case. It will be seen that the bottom of the gear case slopes down towards a low point at which is a hole 280 (see Figure 29). Below this hole, is a transverse bore 281. At the outer end of this bore is a threaded socket 282 into which screws a fitting 283. In a tapered hole in the fitting is mounted a plug valve 284, which has a knob or handle 285, by which it may be rotated. The plug valve is also provided with a recess 286 opening into one side thereof and extending to the inner end of the valve. The inner end of the plug valve is slightly reduced in diameter and fitting over the reduced portion is the end of an open sided sleeve 276, preferably formed of sheet metal and fitting closely within the bore 281 and arranged to turn therein when the plug valve 284 is turned. In order to cause the sleeve 276 to turn with the plug valve, the end of the valve is preferably provided with a recess 288, the metal of the sleeve being depressed into this recess, as indicated at 289. An open slot is left in the sleeve 288 as indicated at 290, this slot corresponding in position with the recess 286 in the plug valve.

Formed on top of the fitting 283 is an oil cup 291 in the bottom of which, communicating with the bore in which the plug valve fits, is an oil hole 292. The oil is supplied to the oil cup 291 from an oil receptacle 293, preferably of glass, which has a neck 294 extending well down into the cup 291, the receptacle 293 also having a flange 295 which surrounds the top of the oil cup, so as to prevent any water or dirt from entering the cup. A finger 296 extending from the side of the separator frame over the top of the oil receptacle prevents accidental displacement thereof. The flow of oil from the receptacle into the oil cup is automatically governed in accordance with the use of the oil, for as soon as the level of the oil in the oil cup rises above the bottom of the neck 294, no more oil will run out of the receptacle

until it is needed. The fitting 283 is provided at its bottom with a drain hole 297. Normally when the separator is in use, the plug is in the position shown in Figure 27, so that there is communication between the hole 221 and the oil chamber 230 in the bottom of the gear case. A constant oil level will be maintained in these two chambers by the oil fed from the receptacle 293. As long as oil is visible in this glass receptacle, the operator will know that the proper oil level is being maintained in the gear casing. Any sediment which collects in the bottom of the gear casing will pass through the hole 280 into the lower part of the sleeve 287. More or less of such heavy sediment will accumulate in this way, consisting mainly of metal particles wearing off the gears. When it is desired to remove this sediment, the plug valve 285 is momentarily reversed thus cutting off the supply of oil from the oil cup 291, and the sleeve 287, closing the opening 280, so that the oil is drained neither from the gear case nor the oil receptacle. The oil which is at the time in the sleeve 287 is, however, drained out through the drain hole 296, carrying with it the sediment which has accumulated in the sleeve. As soon as this oil and sediment has drained out, the plug valve is turned back to the position shown in Figure 29, and the small amount of oil drawn off is replenished from the receptacle 293. The sediment may thus be removed with very little loss of oil.

While I have shown and described in detail certain preferred embodiments of my invention as illustrative of the principles thereof, I do not wish to be limited to the particular constructions set forth as the invention may be embodied in modified constructions. I, therefore, intend to claim my invention broadly in whatever form its principles may be embodied.

What I claim is:

1. A separator bowl having milk and cream outlets, primary and secondary separation chambers, a passage from the primary separation chamber to the cream outlet, a passage from the primary separation chamber to the secondary separation chamber and a passage from the secondary separation chamber to the cream outlet, said passages from the separation chambers to the cream outlet being distinct in the zone separation.

2. A separator bowl having a hollow shaft forming a milk inlet and a member within the bowl forming a partition to divide the interior of the bowl into primary and secondary separation chambers, said member having a sleeve portion surrounding the bowl shaft, said sleeve portion being provided with internal and external cream channels.

3. A separator bowl comprising a bowl bottom having a hollow shaft projecting upwardly therefrom, said shaft constituting a

- 5 milk inlet and having ports formed near the bottom thereof to discharge the milk into the bowl, a bowl shell adapted to be clamped to said bowl bottom, a distributing cone mounted in said bowl, and dividing the bowl space into primary and secondary separation chambers and wings carried by the bowl bottom and dividing said primary separation chamber into sectors.
- 10 4. A separator bowl as in claim 3, in which one of the wings is located immediately in rear of each milk inlet port.
5. A separator bowl comprising a bowl bottom having a hollow shaft projecting upwardly therefrom, said shaft constituting a milk inlet and having ports formed therein to discharge the milk into the bowl, a bowl shell adapted to be clamped to said bowl bottom, a distributing cone mounted in said bowl and dividing the bowl space into primary and secondary separation chambers, and wings located immediately in the rear of each milk inlet port, said ports and wings being arranged substantially tangentially 25 with respect to the hollow shaft.
6. A separator bowl having a bottom provided with a hollow shaft permanently fixed thereto extending upwardly therefrom and providing a milk inlet, a bowl shell adapted 30 to be carried by said bottom, and a distributing cone having a peripheral flange resting upon said bottom and having a sleeve portion surrounding the hollow shaft of the bowl, and defining a cream passage 35 jointly therewith.
7. A separator bowl as in claim 6, in which the peripheral flange of the distributing cone is clamped to the bowl bottom by the bowl shell.
- 40 8. A separator bowl having a bottom provided with a hollow shaft fixed thereto extending upwardly therefrom and providing a milk inlet, said bowl bottom having an annular recess therein, a yielding packing 45 mounted in said recess, a bowl shell carried by said bottom and adapted to engage said packing, the edge of said bowl shell having a shoulder formed thereon, and a distributing cone having a sleeve portion surrounding the hollow shaft of the bowl and having 50 a peripheral flange adapted to engage with the shoulder at the edge of the bowl shell to be thereby held in contact with said packing.
- 55 9. A separator bowl having a distributing element therein dividing the bowl into primary and secondary separation chambers and being provided with outlet ducts for conveying the cream separated from the 60 milk in the primary separation chamber to the cream discharge outlet of the bowl, said distributing element being provided with ports for permitting the milk to pass from the primary to the secondary separation 65 chamber.
10. A separator bowl having a distributing element therein dividing the bowl into primary and secondary separation chambers and being provided with outlet ducts for conveying the cream separated from the 70 milk in the primary separation chamber to the cream discharge outlet of the bowl, said distributing element having a conical wall with a port thereon for permitting the milk to pass from the primary to the secondary 75 separation chamber, and a plurality of conical liner discs stacked in the secondary separation chamber upon the distributing element, each of said discs having an opening 80 therein registering with the port in said distributing element.
11. A separator bowl having means therein dividing the bowl space into primary and secondary separation chambers, and a plurality of liner disks mounted in the secondary separation chamber, the marginal space in the secondary separation chamber outside of the edges of the liner disks being so narrow with respect to the flow therethrough as to maintain the velocity of the milk passing through said space sufficiently high to carry the casein or other sediment out of the bowl with the milk. 85
12. A separator bowl bottom having a hollow shaft extending upwardly therefrom, said shaft and bottom being grooved, and wings mounted in said grooves. 90
13. A bowl bottom as specified in claim 12 in which the wings are held in said grooves by calking. 100
14. A distributing cone for separator bowls comprising a conical portion and a sleeve projecting upwardly therefrom and having cream channels formed interiorly thereof, the walls of said channels being imperforate between the upper and lower ends. 105
15. A distributing cone for separator bowls comprising a conical portion and a sleeve projecting upwardly therefrom and having cream channels formed interiorly 110 thereof and flanges extending partly across the upper ends of said cream channels.
16. A distributing cone for separator bowls comprising a conical portion and a sleeve projecting upwardly therefrom, said sleeve having channels for the ascending cream exteriorly and interiorly thereof in communication with the cream outlet. 115
17. A distributing cone for separator bowls comprising a conical portion and a sleeve projecting upwardly therefrom, said sleeve being formed to provide alternate exterior and interior channels. 120
18. A separator bowl having a central hollow shaft and a distributing cone mounted in said bowl and comprising a conical portion and a sleeve projecting upwardly therefrom and surrounding said hollow shaft, said sleeve having portions engaging the 125 surface of said shaft alternating with por- 130

- tions spaced from the shaft so as to provide cream channels.
19. A distributing cone for separator bowls including a conical portion having an outwardly turned flange at the lower end thereof and discsupporting members on said flange.
20. A separator bowl having a bottom provided with an upwardly extending hollow shaft, a distributing cone within the bowl having a sleeve portion surrounding said hollow shaft, conical liner discs mounted on said distributing cone, a dividing cone mounted above said liner discs and having a neck portion engaging the upper end of the sleeve of the distributing cone and extending above the same, and a bowl shell enclosing said cones and liner discs.
21. A separator bowl having a distributing cone mounted therein, said cone having an upwardly extending sleeve portion formed to provide cream channels, liner disks mounted on said distributing cone and a dividing cone mounted above said liner disks and having a neck portion engaging the upper end of the sleeve of the distributing cone said dividing cone neck being formed with an inwardly turned flange having a cream notch therein.
22. A separator bowl comprising a bottom and a shell, said shell having a neck providing milk and cream outlets, a dividing cone located inside of said shell and having a neck portion extending up into the shell neck, a distributing cone mounted in said bowl and having a sleeve portion extending up to and fitting within the neck of said dividing cone, said sleeve portion having a cream passage inside of the same, extending to the upper part thereof, and liners mounted between said distributing and dividing cones.
23. A separator bowl having a liner therein comprising a stack of liner disks each of which has an outwardly extending peripheral flange, an outer conical portion of steep inclination and an inner conical portion of lesser inclination, said flanges being formed with spacing members for spacing said disks a uniform distance apart, the space at the periphery of the bowl outside of the edges of the disks being narrow so as to maintain the velocity of the milk flow sufficiently high to carry sediment out of said space with the milk.
24. A liner disk for separator bowls having a substantially conical part and a substantially horizontal peripheral flange, said flange being provided at intervals with integral spacing members.
25. A liner disk for separator bowls having a substantially conical body portion and a peripheral flange formed throughout of more than one thickness of metal, said flange being made thicker at intervals to provide spacing portions.
26. A liner disk for separator bowls comprising a substantially conical body portion and an outwardly projecting flange formed by rolling over and flattening down the edge of the metal forming the disk, portions of the metal being flattened down less than other portions so as to provide spacing members.
27. A liner disk for separator bowls having a substantially conical body portion and a peripheral flange formed by folding over the edge of the metal, portions of the edge being folded against the conical part of the disk so as to form spacing members.
28. A liner disk for separator bowls having a substantially conical body portion and an outwardly extending flange, said flange comprising a rolled over and flattened down portion of the metal of the disk, the metal of the flange being flattened down less at intervals so as to provide spacing members for spacing the flanges of successive disks in an axial direction, the edge of the metal where such spacing members are formed being pressed against the conical part of the disk so as to provide spacing members for centering successive disks one upon another.
29. A separator bowl having a liner therein comprising a stack of liner disks each of which is provided with an outwardly extending peripheral flange, said flanges being provided with means for spacing the flanges apart and with means adjacent to said flanges for spacing the conical surfaces of the disks apart.
30. A separator bowl having a shell and a bowl nut fitting thereon, the upper end of the shell having a notch therein forming a cream outlet, the surface of the bowl nut above said notch being beveled.
31. A separator bowl having a shell and a member inside of the shell having a neck provided with a restricted cream outlet, the shell having an opening therein wider than said restricted outlet so as to permit cream to leave the bowl through said restricted outlet without interference from the following wall of the opening in the shell.
32. A separator bowl having a shell provided with a neck, a dividing cone mounted in the bowl and having a neck fitting inside of the bowl shell neck, the dividing cone neck having a cream notch therein, and an opening in the bowl shell neck of greater angular extent than the cream notch, to permit free discharge of the cream leaving the cream notch.
33. A separator bowl having a shell provided with a neck, a dividing cone mounted in the bowl and having a neck fitting inside of the bowl shell neck, the dividing cone neck having a cream notch therein, and an opening in the bowl shell neck extending outward from the notch, much wider than the cream notch to permit free discharge of

the cream leaving the cream notch, the cream notch being positioned near the leading end of the opening of the bowl shell neck.

34. In a separator bowl, a shell having a neck provided with an elongated horizontal opening for the discharge of the blue milk, and a milk discharge regulating the screw located at the leading end of said opening.

35. A separator bowl having a shell provided with a horizontal elongated opening therein for the discharge of the blue milk, the inside of said shell neck having a notch therein communicating with said opening, the bottom of the notch being of greater radius than the radius of that part of the interior surface of the shell neck in which said elongated opening is formed, and a regulating member adapted to have its end projected more or less across said notch so as to vary the radius at which the milk will pass over the end of said regulating member to said milk discharge opening.

36. A separator bowl shell having a neck provided with portions of three internal diameters, the portion of the largest diameter being at the bottom and that of the smallest diameter being at the top, the neck having an elongated slot formed therein and opening at its inner end into the surface of intermediate diameter on the inside of the shell neck, there being a notch formed inside of the shell neck communicating with said slot and a regulating screw screwing into the threaded opening in the shell neck and adapted to have its end projected more or less across said notch.

37. In a centrifugal separator, a separator bowl having an inlet at the upper end thereof, means for feeding the liquid to be separated to said inlet by gravity, and means for supplementing the action of gravity in a variable manner so that the feed will be more rapid when the bowl is being rotated at high speed than when the bowl is turning more slowly.

38. In a centrifugal separator, a separator bowl having an inlet opening at the upper end thereof and having a channel formed in the part thereof around said inlet opening and a feed member mounted above said bowl and having a feed opening located above the inlet opening of the bowl, said feed member having a flange depending into the channel of the bowl member.

39. In a separator, a feed cup having a discharge outlet adapted to discharge directly into the separator bowl, and a float controlled valve governing said outlet.

40. In a separator, a supply can, a feed cup having a discharge outlet, a float in the feed cup, and valve means controlled by said float for governing the discharge from the supply can into the feed cup and the discharge from the feed cup outlet.

41. In a separator, a supply can having a nozzle at the bottom thereof, a feed cup having a discharge outlet at the bottom thereof and having a perforated sleeve extending upwardly from the bottom around said outlet, a float in the feed cup, and a valve carried by the float and adapted to govern the flow from the supply can into the feed cup, said float also carrying a perforated sleeve valve adapted to cooperate with the sleeve in the feed cup for governing the flow from the feed cup through the outlet thereof.

42. In a separator, a bowl having an inlet at the upper end thereof, a feed cup mounted above the bowl and having an outlet registering with the inlet of the bowl, adjacent portions of the feed cup and bowl being formed to prevent free entrance of air into the bowl, and float controlled valve means in the cup for regulating the discharge from the feed cup into the bowl.

43. In a centrifugal separator, a vertical bowl spindle having a tapered upper end and a bowl having a tapered socket in the bottom thereof removably resting upon the tapered upper end of the spindle, the frictional engagement of the tapered surfaces of the socket and spindle constituting the sole means for transmitting the rotation of the spindle to the bowl.

44. In a centrifugal separator, a vertical bowl spindle having a tapered upper end and a bowl having a tapered socket in the bottom thereof resting upon the tapered upper end of the spindle and substantially fitting the same, the length of the engaging portions of the tapered surfaces of the bowl and spindle being comparatively short so that relative movement permitting the bowl to right itself may occur.

45. In a centrifugal separator, a vertical bowl spindle having a spiral gear mounted near the lower end thereof and adapted to be acted upon by a spiral gear having a downward thrust, a step bearing for said spindle located immediately below and close to the spiral gear on the spindle, a yielding neck bearing engaging a spindle above the spiral gear thereon, and a self-righting bowl mounted on the upper end of the spindle at a point below the center of gravity of the bowl, said bowl being supported solely by the spindle.

46. In a centrifugal separator, a short vertical bowl spindle mounted on a step bearing and a bowl mounted in non-rigid position upon the upper end of said spindle at a point below the center of gravity of the bowl, said bowl and spindle being constructed and arranged to spin with a top-like action upon the step bearing.

47. In a centrifugal separator, a short vertical bowl spindle mounted in a step bear-

ing at its lower end and engaged towards its upper end by a yieldable neck bearing, a spiral gear mounted on said spindle close to said step bearing and nearer to said step bearing than to said neck bearing, and a bowl mounted solely on the upper end of said bowl spindle.

48. In a centrifugal separator, a short vertical bowl spindle mounted in a step bearing at its lower end and engaged towards its upper end by a yieldable neck bearing, a spiral gear mounted on said spindle close to said step bearing and nearer to said step bearing than to said neck bearing, the upper end of said spindle being tapered and a bowl having a tapered socket in its lower end at a point below the center of gravity of the bowl, said tapered socket fitting on the tapered end of said spindle, the construction and arrangement being such that both the bowl and the spindle are self-centering.

49. The method of separating cream from milk in stages which consist in treating the whole milk in a primary separation chamber in which the larger globules of cream are separated, treating the remainder of the milk in a secondary separation chamber, separately conducting the cream separated in the two chambers to a cream outlet, and conducting the blue milk to a milk outlet.

50. The method of separating cream from milk which consists in subjecting the whole milk to centrifugal action in a chamber in which the heavier sediment is removed from the milk and retained, and then passing the milk through another separating chamber at such velocity as to sweep out with it any remaining sediment which may be present in the milk.

51. The method of separating a liquid into constituents of different gravities which consists in treating the liquid to a primary separation by which the lighter particles of the lighter constituent of the liquid are removed, conducting such lighter particles to an outlet, subjecting the balance of the liquid to a secondary separation which removes the remainder of the lighter constituent and separately conducting such remaining particles of the lighter constituent to an outlet and separately conducting the heavier constituent to another outlet.

52. The method of separating cream from milk which consists in centrifugalizing the whole milk in a primary separation chamber in which the heavier sediment is collected and in which the larger globules of the cream are separated, and then centrifugalizing the balance of the milk in a secondary separation chamber in which the smaller globules of cream are separated, and maintaining the velocity of the blue milk while passing through and out of said secondary

separation chamber at such speed as to sweep out with it substantially all casein and sediment remaining in the milk when it enters the secondary separation chamber.

53. The method of feeding liquid to a centrifugal separator which consists in permitting the liquid to flow into the top of the separator bowl by gravity and supplementing the action of gravity by a variable factor which increases with the speed at which the separator is operated.

54. The method of feeding liquid to a centrifugal separator which consists in introducing the liquid into the top of the bowl and utilizing the suction created in the bowl to increase the flow of the liquid thereto.

55. In a centrifugal liquid separator, a bowl, a feed device, an annular milk transmitting member surrounding the feed device and located within the bowl, a plurality of liner plates, and means for securing the milk transmitting member in its longitudinal position independently of the liner plates.

56. In a centrifugal liquid separator, a bowl shell, a base for the same, a feed device, an annular milk transmitting member surrounding the feed device and located within the bowl, a plurality of liner plates, and means for securing the milk transmitting member in position between the bowl shell and the base thereof independently of the said liner plates.

57. In a centrifugal liquid separator, a bowl shell, a base therefor, a feed device, an annular milk transmitting member surrounding the feed device and located within the bowl, a plurality of liner plates, and means for connecting the bowl shell to the base through the milk transmitting member to secure the latter in position independently of the liner plates.

58. In a centrifugal liquid separator, a bowl shell, a feed tube, an annular milk transmitting member surrounding the feed device and located within the bowl and associated with the feed tube, a plurality of liner plates, and means for securing the milk transmitting member in position through the bowl shell independently of the liner plates.

59. In a centrifugal liquid separator, a bowl shell, a base therefor, a feed tube, an annular milk transmitting member surrounding the feed device and located within the bowl and associated with the feed tube and the base of the bowl shell, a plurality of liner plates, and means for securing the milk transmitting member in position relatively to the feed tube and base of the bowl shell through the bowl shell and independently of the liner plates.

60. In a centrifugal liquid separator, a bowl shell, a feed device, an annular milk

transmitting member surrounding the feed device and located within the bowl, and means for securing the milk transmitting member in its longitudinal position through 5 the said bowl shell.

61. In a centrifugal liquid separator, a bowl including a shell and a base, a feed tube, an annular milk transmitting member surrounding the feed device and located 10 within the bowl, adapted to seat on the bowl base, and means for securing the milk transmitting member in position relatively to the feed tube through the said bowl shell.

62. In a centrifugal liquid separator, a bowl including a shell and a base, a feed tube, the bowl base being supported on the said feed tube, an annular milk transmitting member surrounding the feed device and 20 located within the bowl, and associated with the feed tube and adapted to seat on the bowl base, and means for securing the milk transmitting member in position relatively

to the feed tube through the said bowl shell and base. 25

63. In a separator bowl, a shell having a neck provided with one or more elongated horizontal openings for the discharge of the blue milk, the rear end or following wall of the opening or openings being inclined rearwardly so as to permit substantially tangential discharge of the milk. 30

64. A separator bowl comprising a bowl bottom having a hollow shaft projecting upwardly therefrom, said shaft constituting 35 a milk inlet and having ports formed near the bottom thereof to discharge the milk into the bowl, a bowl shell adapted to be clamped to said bowl bottom, a distributing cone mounting in said bowl and dividing 40 the bowl space into primary and secondary separation chambers, and wings dividing said primary separation chamber into sectors.

In testimony whereof I have affixed my signature to this specification.

HERBERT McCORNACK.
